UNITED STATES PATENT OFFICE.

FESS CHRISTIANI, OF WASHINGTON, DISTRICT OF COLUMBIA.

RADIO RECEIVING SET.

Application filed May 17, 1924. Serial No. 714,057.

To all whom it may concern:

Be it known that I, FESS CHRISTIANI, a citizen of the United States, residing at Washington, in the District of Columbia, have invented certain new and useful Improvements in Radio Receiving Sets, of which the following is a specification.

This invention relates to improvements in radio receiving sets, and has particular reference to the structure of the set, wherein a receptacle or container is provided adjacent the instrument panel.

An object of the invention resides in providing a radio receiving set mounted in a closed container having a hinged section adapted to be opened to provide access to the instrument panel of the receiving set, provided with suitable manually operable means for tuning the set to receive radio impulses and formed with a slot providing access to a container formed adjacent to the panel.

Another object of the invention resides in providing a housing having a hinged cover section, an instrument panel mounted in the main portion of the housing and adapted to be exposed by the opening of the cover section, inductance windings being provided in the housing having a manual control means on the instrument panel providing the inductance thereof in a radio receiving circuit, said inductance being wound in said housing to provide a receptacle contiguous to said panel, the panel mounting a suitable form of detector electrically connected with the inductance, so that the receiving set contained in the housing may be connected in the proper circuit with an aerial and ground connection, and a sound reproducer, and tuned by the operation of the elements carried on the instrument board for receiving radio signals.

The invention also includes other objects and improvements in the details of construction and arrangement of the parts, which are more particularly described in the following detailed description and in the claim, directed to a preferred form of the invention, it being understood, however, that various changes in the construction and arrangement of the parts may be made without departing from the spirit and scope of the invention as described in the specification and claimed.

In the drawing, forming a part of this application:

Figure 1 is a plan view of the radio re-

ceiving set, showing the instrument panel and the cover in open position.

Figure 2 is a vertical sectional view through the receiving set, showing the cover in closed position, taken on the line 2--2 of Figure 1.

A suitable form of housing is indicated at 1, which is preferably constructed of wood or similar material, having a highly finished outer surface, and is provided with an upper hinged section 2, forming a cover for the main body of the container, indicated at 1, and an instrument panel 3 formed of any insulating material being mounted in the upper open end of the container body 1, in a manner clearly illustrated in the drawing.

The panel preferably is removably fitted in the housing and carries at the back or under side thereof, a plurality of posts 4 projecting in parallel spaced relation at substantially right angles from said panel and carrying at the free ends thereof a plate 5 of suitable insulating material, the corner portions of the plates being adapted to seat on suitable spacing pins 6 in the bottom of the housing 1 for holding said plate, as well as the instrument panel 3, in proper relation in the housing. An inductance coil is provided in the housing by a winding of rectangular form around the post 4, as indicated at 7, from which lead a plurality of caps 8, to corresponding contact points 9, on the instrument panel 3, for interposing desired sections of said windings in a radio circuit, in which it is connected, through the operation of the adjustable contact 10, adapted for operation by the knob 11, in a well known manner. The plate 5 is also provided with inductance windings 12, throughout the length thereof, as indicated in Figure 2, which have caps 13 leading therefrom to other of the contacts 9 on the panel, and which also cooperates with the inductance winding 7 on the posts for tuning purposes in a radio circuit. The panel is provided at 14 with an opening in which is seated a plate 15, having a flange 16 adapted to engage the upper face of the panel 3 to limit the positioning of the plate in the opening, and a suitable form of locking device, indicated generally at 17 is mounted in the panel adjacent the opening and provided with a suitable tongue for locking the plate 15 in the panel. A suitable form of detector, here indicated as a

crystal detector as at 18, is mounted on the plate 16 and electrically connected with the inductance windings 7 and 12 in a well known manner, for cooperation therewith in tuning in a radio signal when properly connected in a radio receiving circuit. The panel is provided at 19 with a plurality of binding posts to which the circuit inductance coils are connected, so that suitable connections may be made therewith to an aerial, a ground, and phones or other sound reproducing device, whereby the structure described may be used as a radio receiving set. The panel is provided, at 20, with a slot, adapted to receive coins, which when inserted therethrough are housed within a container formed at the rear or bottom of the panel by the windings 7, and 12 of the radio receiving set, so that the same may be used as a bank, for saving coins of various denominations, which will act in conjunction with the inductances 7 and 12, to furnish a capacity operating in conjunction therewith, in receiving radio signals. The cover 2 is also provided with a slot indicated at 21, which when said housing is closed, is positioned over the slot 20, while an elongated slot sleeve 22 is mounted on the inner face of the cover around said slot, and is adapted to extend into proximity to the slot 20, so that coins may be inserted in the slot 21 and guided by the sleeve 22 through the slot 20, into the container or receptacle below panel.

It will be seen from the foregoing construction that a novel form of radio receiving set has been provided, which will efficiently receive radio signals, and which is constructed to form a container or receptacle in the rear of the panel 3, adapted to receiving coins and like denominations of money, so that the same will form a savings bank therefor, the coins at the same time, while being saved, cooperating with the receiving set, for increasing the efficiency, and aiding in the reception of signals thereby.

What I claim is:

In a device constituting a part of a radio receiving set, a housing having an open panel mounted on the open end of the housing, a plurality of rod members mounted on the panel and projecting laterally thereof, a plate mounted on the free end of the members, a coil of wire mounted on rods and plates and contained within the housing, said coil forming a closed container on one side of said panel and adapted to serve as an inductance, said panel being formed with a slot to permit the insertion of metallic elements into the container.

In testimony whereof I affix my signature.

FESS CHRISTIAN
